UNITED STATES PATENT OFFICE.

SAMUEL SPEER, OF PITTSBURG, PENNSYLVANIA.

TROLLEY-POLE.

933,208.

Specification of Letters Patent.

Patented Sept. 7, 1909.

Application filed March 29, 1909. Serial No. 486,468.

To all whom it may concern:

Be it known that I, SAMUEL SPEER, a citizen of the United States, residing at Pittsburgh, in the county of Allegheny and State 5 of Pennsylvania, have invented certain new and useful Improvements in Trolley-Poles; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 My invention relates to trolley-poles for conducting electric currents from overhead wire to the motor feed wires of the car, the object being to provide a pole capable of yielding vertically as well as in the direction of travel, and which can be raised and lowered from one end of the car by the operation of a hand-lever.

With the above objects in view my invention consists in the peculiar construction 25 and combination of parts as will be herein-after more particularly described in the specification and pointed out in the appended claims.

In the accompanying drawings forming a 30 part of the specification, Figure I, is a side elevation of a portion of the car top having my improved trolley-pole connected thereto and in operative engagement with the trolley-wire. Fig. II, is a rear elevation of the 35 pole disconnected from the car, and Fig. III, is an enlarged side elevation of the trolley-wheel and attending trolley-guides, detached from the pole, the detail portions of the structure being designated in the several 40 views by numerals of like character.

In carrying out my invention, I employ a plate 1 secured to the top of the car 2, and pivotally secure to the transverse pin 3 carried by the plate, the lower end of the tubular trolley-pole section 4, said pole section 45 being further secured to the ends of the said plate, from an intermediate point thereof, by means of the downwardly disposed spiral springs 5, so that the same may yield in either a forwardly or rearwardly direction 50 and at the same time be under tension. Loosely fitted at its lower end into the said tubular section in the upper trolley-pole section 6 which carries a spiral spring 7 thereabout to engage the upper end of the 55 lower section so that it may yield to vertical

movement, said upper pole section carrying a trolley-wheel 8 for engagement with the trolley-wire 9. This upper section of the pole has suspended upon its wheel axle, one 60 at each side of the wheel, a gravitating guide 10, the upper end of which inclines toward and projects over the edge of the wheel so as to guide the wheel to the trolley-wire in replacing same, the lower end of said guide 65 being weighted so as to normally assume a vertical position at all times regardless of the inclination of the pole. At each side of this trolley-pole proper, is arranged a parallelogram, composed of four like members, 70 12, 13, 14 and 15 pivotally connected at their intermediate and end meeting points so as to be capable of vertical adjustment, the upper ends being pivoted upon the wheel axle and the lower ends to the aforesaid transverse 75 pin 3 carried by the plate 1.

Each of the parallelograms has connected to its intermediate pivotal points a pair of links 15', the meeting ends of which links are pivotally connected to the upper end of 80 the rod 16 which has its lower end likewise connected to links 17 and 18, said link 17 being arranged at its opposite end upon the aforesaid pin 3 and the latter to the hand-lever 18' which is fulcrumed upon the forward 85 end of the car, by means of the rod 19.

In practice, the trolley pole and attending connections assume the position shown by the full lines at Fig. I, and should it accidentally, or otherwise, be removed from its 90 position of service the lever 18' is pulled, causing the said pole and attending parts to assume the position shown by the dotted lines on said Fig. I, and upon releasing the said hand-lever it resumes its operative position, but should the trolley-wheel not be exactly in a vertical line beneath the trolley-wire, said wire will be engaged by either one of the gravitating guides and caused to be guided to the wire. 95

In adjusting the trolley-pole so as to bring the wheel into engagement with the trolley-wire the guides will not only operate to direct the wheel to the wire, but when in practice the said guides will not interfere with 105 the guy-wires they being capable of adjusting themselves to pass under the guy-wires when encountered, in either direction of travel, as will be apparent from the view shown at Fig. III, in which the guide is 110 shown in normal position as well as in abnormal in passing under the guy-wire, the

latter positions being shown by dotted lines, said guy-wires being designated by the numeral 20.

Having thus shown and described my invention, what I claim and desire to protect by Letters Patent, is:

1. A trolley-pole, comprising a trolley-pole proper formed of two sections, the upper section telescoping into the lower section and carrying a trolley-wheel at its upper end and said lower section pivotally secured at the car top so as to permit the pole adjustably inclining toward either end of the car, a pair of spiral-springs each connected to an opposite side of the pole in the direction of its inclination each being disposed at an angle and connected at their lower ends at the car top so as to place tension on the movement of the pole in either direction, a spiral spring carried by the upper section of the pole and engaging the upper end of the lower section so as to place tension on the vertical movement thereof, a parallelogram disposed at each side of the trolley-pole and adjustable therewith the outer extremities being pivotally connected to the axis of the trolley-wheel and that of the pole base, a pair of links connecting the intermediate pivotal points of the parallelogram, a rod connecting the meeting ends of said links extending downwardly to and connecting with a link carried by the pivot of the trolley base, a hand-lever carried upon the front of the car top, and a rod connecting the hand-lever with said rod and link.
2. A trolley-pole, comprising a trolley-

pole proper formed of two sections, the upper section telescoping into the lower section and carrying a trolley-wheel at its upper end and said lower section pivotally secured at the car top so as to permit the pole adjustably inclining toward either end of the car, a pair of spiral-springs each connected to an opposite side of the pole in the direction of its inclination each being disposed at an angle and connected at their lower ends at the car top so as to place tension on the movement of the pole in either direction, a spiral-spring carried by the upper section of the pole and engaging the upper end of the lower section so as to place tension on the vertical movement thereof, a parallelogram disposed at each side of the trolley-pole and adjustable therewith the outer extremities being pivotally connected to the axis of the trolley-wheel and that of the pole base, a pair of links connecting the intermediate pivotal points of the parallelogram, a rod connecting the meeting ends of said links and extending downwardly to and connecting with a link carried by the pivot of the trolley base, a lever carried by the front of the car top, a rod connecting the hand lever with the said rod and link, and members suspended upon the trolley-wheel axis to guide the wheel to the wire.

In testimony whereof, I affix my signature, in presence of two witnesses.

SAMUEL SPEER.
